UNITED STATES PATENT OFFICE.

HOWARD W. STEIGER, OF LAKEWOOD, OHIO, ASSIGNOR OF ONE-HALF TO HAROLD M. STEIGER, OF CLEVELAND, OHIO.

DESIGN FOR A FONT OF PRINTING-TYPE.

No. 39,146.

Specification for Design.

Patented Feb. 18, 1908.

Application filed December 23, 1907. Serial No. 407,852. Term of patent 14 years.

To all whom it may concern:

Be it known that I, HOWARD W. STEIGER, a citizen of the United States, residing at Lakewood, in the county of Cuyahoga and State of Ohio, have invented a new, original, and ornamental Design for a Font of Type, of which the following is a specification.

My invention relates to a new, original, and ornamental design for a font of printing-type the nature of which is fully and clearly shown in the accompanying drawings in which are comprised capital and lower-case letters, dollar and pound symbols, punctuation-points, and numerals whose characteristic points or features are the enlarged angularly-extended obliquely-concaved terminal portions terminating in cut-offs opposite the apices thereof.

What I claim is,—

The design for a font of printing-type as herein shown and described.

HOWARD W. STEIGER.
